HARRY YARRINGTON ARMSTRONG, OF ELGIN, ILLINOIS, ASSIGNOR, BY MESNE ASSIGNMENTS, TO PACKAGE MACHINERY COMPANY, OF SPRINGFIELD, MASSACHUSETTS, A CORPORATION OF MASSACHUSETTS.

GUM-WRAPPING MACHINE.

1,187,800.

Specification of Letters Patent. Patented June 20, 1916.

Application filed February 14, 1913; Serial No. 748,305.

To all whom it may concern:

Be it known that I, HARRY Y. ARMSTRONG, a citizen of the United States, and a resident of Elgin, in the county of Kane and State of Illinois, have invented certain new and useful Improvements in Gum-Wrapping Machines; and I do hereby declare that the following is a full, clear, and exact description thereof, reference being had to the accompanying drawings, and to the characters of reference marked thereon, which form a part of this specification.

This invention relates to improvements in wrapping machines.

15 The machine herein illustrated has been designed for wrapping flat, thin articles, such as sticks of gum, and in the following description the features of construction and operation will be specifically referred to with 20 respect to such a machine, although it will be understood that some of the features illustrated and described may be employed for wrapping articles of other sizes and shapes. The machine shown is also designed 25 to wrap articles with an inner and an outer wrapper, the inner wrapper being usually a thin, light paper, such as oil paper, and the outer wrapper a heavier paper on which is printed the label of the article.

30 The machine herein shown is designed more specifically for wrapping individual cakes, which are known as vending machine cakes, in which the outer wrapper is made only of sufficient length to cover the inner 35 wrapper but is not provided with end flaps to inclose the ends of the package.

Among the objects of the invention is to provide a compact and simple wrapping machine which is capable of being operated 40 at a high speed to efficiently wrap articles, such as chewing gums, and the invention consists in the matters hereinafter set forth and more particularly pointed out in the appended claims.

45 In the drawings:—Figure 1 is a partial side elevation, with parts broken away, of a wrapping machine embodying my invention. Fig. 2 is an enlarged side elevation of part of the machine shown in Fig. 1. 50 Fig. 3 is a partial side elevation and partial central vertical section of the machine. Figs. 4 and 5 are horizontal sections on the lines 4—4 and 5—5, respectively, of Fig. 2. Fig. 6 is a vertical section on the indirect

line 6—6 of Fig. 2. Figs. 7 and 8 are detail vertical sections on the lines 7—7 and 8—8, respectively, of Fig. 2. Fig. 9 is a detail section taken on the line 9—9 of Fig. 4. Fig. 10 is a fragmentary detail of the primary wrapper head and the parts associated therewith. Fig. 11 is a fragmentary perspective view of the end folding mechanism for the inner wrapper, located in advance of the primary wrapper head. Fig. 12 is a perspective view of the primary wrapper head separated from its co-operating parts. Fig. 13 is a perspective view illustrating the secondary wrapper head, a portion of the pasting mechanism and a portion of the tertiary folding slot. Figs. 14 and 15 are fragmentary sectional views of the secondary wrapper head and associated parts of the secondary and tertiary folding slots. Fig. 16 is a horizontal section on the line 16—16 of Fig. 2. Fig. 17 is a horizontal section 75 on the indirect line 17—17 of Fig. 2. Fig. 18 is a vertical section on the line 18—18 of Fig. 2.

The machine is mounted on a base or pedestal 20 which carries upright webs or flanges 21, 21 which support the wrapping mechanism and the bearings for the various operating shafts.

22 designates the main operating shaft of the machine mounted in bearings carried by 85 the webs 21 at the front end of the machine and is provided with a pulley 23 through which power is transmitted thereto, as by the belt 24.

The gums *c* to be wrapped are stacked in 90 a vertical hopper 26 suitably supported over the primary folding slot 28 formed between upper and lower plates 29, 30, respectively. The lowermost gum of the stack rests in the primary folding slot and the gums are advanced through said slot from the lower end 95 of the stack by means of the primary plunger 32 which reciprocates in the slot and through the lower end of the hopper. The said plunger 32 is attached to the upper end 100 of and moves with a vertically arranged cross head 33 at the side of the machine which is apertured at vertically spaced points to fit over the reciprocable rod 35 and guide rod 36. The head is attached to the reciprocable rod in any suitable manner. The guide rod 36 is mounted at its ends in bearings 37, 37 carried by the machine frame.

The actuating rod 35 slides in bearing in the bearing members 38, 38 carried by the machine frame. The rod 35 is reciprocated by power derived from the main operating shaft 22 through the medium of the crank 39 on said shaft and a pitman or link 40 pivoted at one end to said crank and at the other end to a head 42 attached to the forward end of the rod 35.

10 The gums are forced by the plunger 32 through the slot 28 into the alined pocket 45 of an intermittently rotative wrapper head 46 (Figs. 1, 2, 3, 10 and 12) arranged at the delivery end of the slot 28. Said primary 15 wrapper head 46 is formed on or carried by one end of a rotating shaft 48 that is mounted in a suitable bearing 49 on the adjacent web 21, as best shown in Figs. 4 and 10. Said wrapper head embraces a central body 20 portion having at its upper and lower sides hooks or flanges 50, 50 between which and the central body of the head are formed the gum receiving pockets 45. Each side of the head is centrally slotted to receive a spring 25 pressed member 52 which is pivoted to the body and which extends over the pockets, and their free ends are pressed toward the bottom of the pockets by springs 54 so as to hold the gums in the pockets, as best 30 shown in Figs. 3 and 12. Said primary wrapper head 46 is narrower than the length of the gums, while the wrappers are longer than the gums. The shaft 48 which carries the primary wrapper head is formed at the 35 side of the head with rectangular enlargements 63, 63 to support the extended end flaps of the wrappers. The forked ends of the primary plunger extend over these enlargements at the forward limit of their 40 throw and said enlargements are cut away at 64, 64 to permit the head to begin to rotate before the plunger clears the same in its retractive movements. The pocket 45 at the upper side of the head faces toward and 45 is normally in line with the folding slot 28, while the pocket at the lower side of the head faces oppositely to and is in line with a secondary folding slot 60 associated with the end flap folding mechanism. The latter 50 slot is formed between upper and lower plates 61, 62, respectively. The plate 62 constitutes the floor of the slot 60, and extends a distance forwardly from the upper plate 61. It is notched to partially receive 55 the primary wrapper head. The upper plate 61 is specially formed to coöperate with the end flap folding devices, hereinafter to be described.

60 The inner wrappers, designated by *a*, are cut from a continuous strip *a'* of thin paper by a suitable feeding and cutting mechanism, designated by 65, which need not be here described. The upper wall 29 of the primary folding slot is notched at 66 to 65 permit the cut wrappers to be fed across the

said slot and into the path of the gums. The rear end of the lower wall of the slot 28 is formed by a block 30' suitably attached to the upper wall as by the screws 30², (Fig. 2) and between said block and the wall 30 70 is formed a space to receive the lower portions of the wrappers. The cut wrappers are supported in this position by the stop or stops 67 carried by the block 30'. When the advance edge of the gum, urged forward by the plunger 32, strikes the inner wrapper it folds one side of the wrapper about the advance marginal portion of the gum and, in the continued forward movement of the plunger, the gum and its partially 75 folded wrapper are delivered into the upper pocket 45 of the primary wrapper head 46. It should be noted that the advancing movement of each stick of gum or of a part that moves a stick of gum is termed its forward 80 movement although this direction of movement is rearward with regard to the machine itself; that is, the gum magazine 26 is regarded as positioned at the front of the machine and the stacker 235 at the rear of 85 the machine.

I may provide means for creasing the end flaps at their rear edges as they leave the primary folding slot, in the manner indicated at α^2 in Fig. 10, so as to thereby tuck 90 in the material of the flap and avoid too great fullness, or a bunching effect of the wrapper, when the end flaps are folded against the sides of the packages. This may be effected by providing the primary plunger at its lower margins with grooves 68 which open entirely to the forward ends of the plunger, and providing creaser plates 69, one at each side of the primary folding slot, attached to the wall of the slot in any 95 suitable manner and adapted to extend toward each other into the slot. As herein shown, the creaser plates 69 are carried by a bracket 69' attached to the rear face of the block 30'. The horizontal portion of 100 the bracket is extended toward the wrapper head 46 to support the wrapper while being passed to said head. The said creaser plates are formed at their inner ends and at their 105 forward sides with curved edges which are 110 arranged in line with and are adapted to co-operate with the grooves 68 of the plunger to crease the end flaps in the manner shown in Fig. 10.

After the partially wrapped gum has been 115 thus delivered to the primary wrapper head 46 said head is partially rotated to bring the pocket carrying the same in line with the secondary folding slot 60 and to bring the other pocket thereof in line with the 120 primary folding slot 28 to receive another 125 gum and wrapper in the next forward movement of the plunger 32. The said plunger 32 is notched at its forward end, as indicated at 70 in Fig. 4, to snugly receive the gum c 130

so as to thereby hold the gum laterally alined in the slot during its movement there-through. In order to prevent the gum from clinging to the forward end of the plunger 32 when it is retracted, after delivering a gum to the primary wrapper head, I may provide the delivery end of the lower wall of the primary folding slot, formed by the block 30', with a spring pressed dog 72, the rear end of which plays upwardly through the slot 73 formed in the said block, so that the free end of the dog is slightly above the lower wall of the slot. The dog yields downwardly against a spring 74 to permit a gum to pass by the same into an alined pocket of the primary wrapper head, and after the gum has passed the dog it springs upwardly into a central notch 75 formed in the plunger 32, so as to bring the free end of the dog in front of the gum. The free end of the dog, at this time, constitutes a stop to prevent the gum being retracted with the plunger.

When the gum and its wrapper have been delivered in alinement with the secondary folding slot 60, as most clearly shown in Figs. 3 and 7, the free side margin of the wrapper bears against a bar 78 arranged transversely across the end of the upper wall plate 61 of the secondary folding slot, and made of a length greater than that of the wrapper. The said bar is fastened to the wall plate 61 in any suitable manner, as by the screws 79 shown in Fig. 11. The free margin of the wrapper is thus held throughout its length in advance of the gum so that when the gum is advanced by the means hereinafter described, said margin is folded over the upper side of the gum to complete the side folding thereof. The said bar 78 is provided exterior to the secondary folding slot with down-turned ends 82 provided with inwardly turned parts 82' formed with oblique folding surfaces 83, the lower inner portions of which are substantially in the plane of the upper surface of the bottom wall plate 62 of the secondary folding slot. The down-turned portions 82 are spaced apart a distance greater than the length of the inner wrapper, thus permitting the wrapper and gum to pass freely between the same. Fixed to the sides of the said lower wall plate, as by the screws 84, 84 are end folding plates 85, 85 having upwardly facing oblique folding edges 86, 86, the lower or forward ends of which, at the forward ends of said plates, are substantially in the plane of the upper face of the lower wall of the secondary folding slot and the inner lower parts of the folding surfaces 83 of the bar 78, as best shown in Fig. 11. The upper wall plate 61 is narrower than the lower wall plate 62 between said folding plates 85 so as to thereby leave spaces 61' through which the upwardly folded end flaps of the wrapper may pass, as shown in Fig. 8.

The sides of the upper wall plates of the secondary slot, abreast of the folding plates 85, 85 are provided with creaser plates 61' which extend slightly below the level of the upper wall plate so as to crease the end flaps 70 of the inner wrapper at the bases of said flaps and thereby facilitate the folding of the said flaps upwardly about the package. The transverse bar 78 may be arranged at its inturned portions 82' to bear against one set of screws 84 of the folding plate 85, as best shown in Fig. 11, so as to support the forward or receiving end of the upper wall plate 61 on said screws, and prevent said latter plate tilting upwardly at its rear end 80 in a manner to tilt the forward end thereof downwardly which would result in obstructing or partially closing the receiving end of the secondary folding slot.

The upper wall plate 61 of the secondary folding slot is provided in advance of said folding plates 85 with recesses 87 arranged at the sides of the longitudinal center of the plate, and these recesses have converging exterior side walls 88, 88 to constitute folding surfaces to fold the upwardly extending end flaps of the wrapper downwardly against the flat top side of the package as it progresses through said slot. The said recesses are arranged at their forward inclined 95 margins 88 substantially in the planes of the inner sides of the folding plates 85 so as to smoothly guide the wrapper end flaps from the folding plates onto the folding edges constituted by the converging recess walls. The lower wall plate 62 of the secondary folding slot is formed in rear of the folding plates 85 with marginal upstanding ribs 89 on which the widened rear portion of the upper wall plate rests, thus forming in the lower wall plate between said ribs a depression for the package of gum and wrapper, as best shown in Fig. 9. The said oblique side walls of the recesses 87 taper gradually inwardly toward their rear ends over the ribs 89 so as to form overhanging portions 90 to gradually bring the upstanding end flaps, shown in Fig. 8, flat down on the upper side of the package, as shown in Fig. 9. The intermediate portion 90' of the top wall plate is narrower than the distance apart between the folded down wrapper ends so as not to interfere with the discharge of the package from the secondary folding slot. The said gum and wrapper are forced from the primary wrapper head and into the secondary folding slot by means of a secondary plunger 91 having at its rear end laterally separated members 92, 92 spaced apart such distance as to pass one on each side of the primary wrapper head, as indicated in Fig. 5, the wrapper head being made narrower than the length of the gum. The said secondary plunger is actuated in unison with 130

the primary plunger, it being shown as fixed to a ledge or flange 93 of the cross head 33.

The stroke of the plunger 91 is of sufficient length to carry the wrapped gums 5 from the secondary folding slot into the slot 95 of a secondary wrapper head 96 which is mounted on or carried by a shaft 97 that is rotatively mounted in suitable bearings 98 supported on the web 21. The 10 slot 95 of said secondary wrapper head is normally in line with the secondary folding slot. The head is separated by a narrow space from the walls of the secondary folding slot to provide a wrapper receiving 15 space or recess to receive an outer wrapper b , adapted to be fed into said space or recess from the wrapper feed mechanism.

The wrapper feed mechanism embraces a magazine 98, that is pivotally supported 20 on a shaft 99 mounted in the frame of the machine, and a stripper roller 100 arranged to bear against the group of wrappers b at the discharge end of the magazine, with its shaft 101 mounted, in any suitable manner, 25 in bearings 102 carried by and projecting forwardly from the magazine. The said stripper roller is adapted to be rotated through the medium of meshing pinions 104, 105 carried by the shaft 101 and a shaft 30 106, the latter arranged at the side of the magazine and mounted in bearings 107, 107 carried by the magazine. The said shaft 106 is driven from the shaft 99, by the intermeshing beveled pinions 108, 109, as 35 shown in Figs. 1 and 2. The construction described permits the forward end of the magazine and the roller carried thereby to be swung upwardly so as to carry the roller away from the wrapping mechanism beneath the roller. The magazine is locked 40 in its lower position by means of a split lug 410 which depend therefrom at its inner side in overlapping engagement with the lug 411 on the frame, and a clamp bolt 412 extends 45 through the split lug and is screw-threaded to the lug 411. The split lug is clamped against the lug 410 by a shoulder 412' on the bolt. The said bolt is provided with a handle 413 by which it may be turned into 50 and out of clamping position.

The magazine is provided beneath the forward end thereof and in rear of the stripper roll with a guide member 110 to 55 guide the wrappers from the roller to the wrapper receiving recess below. There is also provided just in front of the upper end of the wrapper recess and in rear of the stripper roller a guard 111, (Figs. 3 and 11) which is herein shown as fixed to the 60 rear end of the upper wall plate of the secondary folding slot. This guard avoids tendency of the wrappers following the stripper roller and insures accurate delivery of the outer wrappers into the wrapper receiving recess below. The wrapper receiv-

ing recess is inclosed by side walls 114, 114 and a curved front wall 115 which is formed on or carried by a bracket 116, and the wrapper rest or support is formed by a member 117 which is attached to and extends forwardly beneath the bracket 116. 70

As a further and separate improvement, the secondary wrapper head is formed at opposite sides of its slot or pocket, and adjacent to the ends thereof, with curved 75 horns 120, 120, the outer surfaces of which are curved concentrically to the axis of rotation of the secondary wrapper head. These horns are notched at 121 to clear the finger 217 hereinafter described. The side 80 walls of the wrapper receiving recess are curved at their upper sides to correspond to the exterior curvature of said horns and one of the horns, in the normal position of the wrapper head, lies in a position to constitute, in effect, a portion of the rear wall of the wrapper receiving recess, and serves to guide the wrapper to the bottom or wrapper support of the recess, as best shown in Figs. 3 and 14. 90

The pocket of the secondary wrapper head 96 is herein shown as made longer than the width of the gums which pass therethrough. Within said pocket is located a floating plate 122, best shown in Figs. 3, 95 14 and 15, which is made of a width approximately one-half of the length of said pocket. Said plate is adapted to slide from one end to the other of the pocket, and is held in place and is guided in its sliding 100 movement by means of a pin or stud 125 which extends downwardly through an opening in one wall of the pocket to engage a guide slot 125' therein. The stud is carried by a spring 126 that is attached to the 105 wrapper head just exterior to its bearing. The said spring is slotted to receive the headed end of the pin or stud 125, and is provided with a terminal finger 127 which extends slightly beyond the lateral edge of 110 the head so that it may be engaged by the finger to raise the spring and withdraw the guide stud from the slotted floating plate when the latter is to be removed. The said plate is provided with a hand piece or projection 128 by which the plate may be removed when the guide stud is released therefrom. 115

In the operation of the secondary wrapper head and the secondary plunger to apply the outer wrapper to the packages wrapped with the inner wrapper, the floating plate 122 lies at the receiving end of the pocket, when the wrapper head is in position to receive a package from the secondary folding slot, as shown in Fig. 3. When the package is delivered to the pocket its front edge engages the floating plate and pushes the same forwardly through the 125 pocket. The movement of the plate under 130

the influence of a following package also serves to push a preceding package ahead of the same out of the secondary wrapper head into the tertiary folding slot 130 arranged horizontally in line with the pocket. When the packages are forced into the pocket of the secondary wrapper head they strike the outer wrappers *b* and fold one side or margin about one side of the package. Thereafter the wrapper head is turned 10 a partial rotation, in the direction indicated by the arrow in Fig. 14, to bring the end of the pocket which has just received a package adjacent to the tertiary folding slot and its other end adjacent to the secondary folding slot to receive another package. The lower or free margin of the outer wrapper is drawn out of the wrapper receiving recess during said partial rotation of 15 the secondary wrapper head and trails behind the package just inserted into the pocket, so that when the package is forced from the pocket into the tertiary folding slot the said trailing margin of the wrapper 20 is folded flat against the under side of the package to complete the folding of the outer wrapper. After the secondary wrapper head has been given the one-half rotation in position to direct a partially wrapped package into the tertiary folding slot, the trailing edge or margin of the wrapper is brought to lie against a rearwardly facing pasting surface 134 on an upstanding part 135 of a bracket 136 which projects laterally 25 from and is carried by the web 21, as most clearly shown in Fig. 6. At this point the paste is applied to the forward surface of the wrapper margin, which constitutes, when the margin is folded against the package, 30 its inner face, so that when the trailing margin of the wrapper is folded up against the package, the paste applied thereto causes the margin to adhere to the opposite or first folding margin of the wrapper. 35 I have herein shown a novel mechanism for applying the paste to the wrapper, which is made as follows:

137 designates a short shaft which extends from front to rear of the machine and 40 is mounted at one end in the bracket 136 and at its other end in a bracket or bearing 138 of the machine frame. Mounted on the front end of said shaft 137, in front of the bracket 136, is a collar 140. Extending 45 through said collar and through the shaft is a rod 141, said rod extending beyond said collar to constitute a bearing for an axially apertured paste applying arm 142. The said rod 141 is headed at its upper end to engage the outer end of the paste applying arm to hold it thereon, and is detachably fixed in the collar 140 so that it may be endwise removed therefrom to permit the removal of the paste applying arm. As herein 50 shown, this attachment is effected by means

of a screw 145 which is screw-threaded in the collar and engages at its inner end an annular socket in the rod 141. The said paste applying finger is provided at its outer or upper end with a paste applying projection 70 146 which is adapted to be swung past the pasting face 134 in contact with the margin of the wrapper lying against said face. The said paste applying finger 142 is provided at its inner end with a miter gear 150 which 75 meshes with a fixed beveled annular rack 151 formed on the face of the bracket 136. With this construction, when the shaft 137 is rotated it serves, by reason of its connection with the paste applying finger, through 80 the rod 141, to revolve said pasting finger about the axis of said shaft; the engagement of said gear on the paste applying finger with the annular rack 151 causes the said finger to simultaneously rotate about its own 85 axis. The paste applying projection of said finger is brought into contact with a paste bearing surface in one part of its revolution to receive paste and in another part of its revolution is brought into contact with the 90 wrapper (Fig. 3) so as to transfer the paste to the wrapper. From the construction described, it will be seen that the paste applying projection has a rolling contact with the paste applying surface and the wrapper, as 95 distinguished from the wiping contact. This construction possesses the important advantage of avoiding any tendency of the paste applying finger to shift or displace the wrapper when transferring the paste thereto, such as would occur if the paste applying finger passed with a wiping contact across the face of the wrapper.

The path of the projection of the paste applying finger across the wrapper is a 105 curved or arcuate path (Fig. 6). In order to avoid applying paste to the pasting face when no wrapper is present, I may provide said pasting face with a recess or depression 154 parallel to the path of the paste applying projection of said finger.

The means for transferring the paste to the paste applying finger comprises a rotative disk 156 located beneath the shaft 137 and having one face substantially in the 115 plane of the pasting face. Said disk rotates in a body of fluid paste contained in a paste pot 157, and is mounted to rotate on a shaft 158 which has suitable bearing in the wall of the paste pot. The upper wall of the 120 paste pot is provided with an opening through which the disk extends, and is provided also at one side of said opening with a guard or hood 160 having a curved lip 161 which partially overlaps the periphery of 125 the disk. Said top wall is hinged at 163 to one side wall of the paste pot so that the same may be swung upwardly to charge the paste pot, and the swinging wall is locked in position by means of a swinging or hinged 130

locking latch 165 hinged to the paste pot wall and adapted to be swung upwardly into a notched portion 166 of said swinging top wall.

5 168 designates a scraper arranged to scrape excess paste from the rising side of the disk. Said scraper is carried by the upper end of an arm 170 which is hinged at 171 to the lower side of the paste pot. The 10 said scraper is pressed toward the disk by means of a spring 172 that surrounds a rod 173 which extends through said arm 170 and into the adjacent wall of the paste pot, the spring being interposed between said 15 arm and a shoulder at the outer end of said rod. The movement of the scraper toward the disk is limited by a screw-threaded stop 175 which is screw-threaded through the arm 170 and bears against the adjacent wall 20 of the paste pot, and said screw stop is locked in place by a lock nut 176 that is screw-threaded to the stop and bears against the outer face of said arm 170. The said paste disk shaft is geared to the paste applying finger shaft by means of the pinion 178 on the latter shaft which meshes with the gear wheel 179 on the paste disk shaft. The said paste applying finger shaft is driven from a shaft 181 mounted in the 30 frame of the machine through the medium of a beveled pinion 182 on said latter shaft which meshes with one face of a double beveled pinion 183 carried by a short vertical shaft 184 that is mounted in bearings 185, 35 185 carried by the machine frame. The other gear face of the double pinion meshes with a pinion 186 fixed to the paste applying finger shaft 137.

In order to prevent the paste applied to 40 the trailing margin of the wrapper from objectionably smearing the under side of the secondary wrapper head 96, when the packages are forced from the pockets thereof into the tertiary folding slot 130, the sides of 45 said wrapper head at the end openings of the pockets, and opposite to the horns 120, are depressed so as to leave laterally separated ribs or projections 190, as best shown in Figs. 4, 13, 14 and 15. These ribs or 50 projections are made with sharp or narrow edges so that the paste that may adhere thereto, as the pasted flap wipes over the same, will be so small as to be negligible.

The tertiary folding slot 130 is formed 55 principally between an upper plate 192 and a series of rollers 193, 193 arranged in two sets at the sides of the longitudinal center of the slot, with their shafts mounted in bars 195, 195 at the sides of the slot and intermediate plates 196, 196 (Figs. 5 and 13) arranged centrally of the slot. The said upper plate 192 of the tertiary slot is removably supported in place on the bars 195 by means of swinging, spring actuated locking latches 60 198 which are pivoted at 199 (Figs. 2 and

18) to said bars and are adapted to swing upwardly into engagement with slotted lugs 200 formed on the sides of the plate 192, as best shown in Figs. 2, 4, and 18. By swinging the latches outwardly in the manner indicated in the dotted lines at the right of Fig. 18, the plate may be removed so as to afford access to the wrapped packages in the slot.

At the entrance of the slot there is arranged a presser device for engagement with the packages to hold the same firmly against the bottom of the slot. It consists as herein shown, of a plate 202 that is hinged at 203 at the top wall plate of the slot, and carries at its rear end a roller or rollers 204 which project beyond the upper wall of the slot for engagement with the upper sides of the packages. Said presser device is yieldingly pressed toward and upon the packages by means of a spring 206 which surrounds a rod 207 extending upwardly from the top wall plate of the slot and through an opening in the presser plate; said spring bearing against the presser plate and a shoulder 90 at the upper end of the rod. An adjustable screw stop 208 limits the movement of the presser roller or rollers toward the packages.

The packages are discharged from the pockets of the secondary wrapper head and into the receiving end of the tertiary folding slot by the action of the secondary plunger 91. They are forced through the tertiary folding slot by an intermittently actuated feed device which is made as follows: 210 designates a horizontally reciprocable slide arranged beneath the tertiary folding slot with its edges engaged with and sliding in grooves or tracks 211 at the sides of the lower wall plate of the slot. 105 The said slide carries a swinging spring pressed finger 214 that is pivoted at 215 to the slide and extends forwardly therefrom, and is provided at its forward end with a tooth 216 and an inclined or beveled end 217. A spring 218 (Fig. 3) acts on the finger to press the same toward the packages. Means are provided for reciprocating the slide and finger so as to move the finger toward the head 96 to engage the rearward 110 edge of the package and to thereafter intermittently move the same forwardly there-through. The said finger 214 is shown in Fig. 15 in its rearmost position, at which time its actuating spring has swung the 115 tooth 216 upwardly into engagement with the package so as to advance the package rearwardly into the slot a distance equal to the width of a package in the next forward movement of the finger. The advanced position of the finger is shown in Fig. 3.

The means herein shown for giving reciprocating movement to the finger consists of a cam 220 that is fixed to the paste applying finger shaft 137 in rear of the bracket 136. 125

Said cam is provided with an external cam groove 221, and the slide 210 is provided with a downwardly projecting lug having a bearing roller 222 to engage into said cam groove. The said cam groove 221 is provided with a short straight portion 223 at one part, (Fig. 16) which is the part in which the lug lies when the feed finger is in its forward position, so as to give to 10 the finger and its slide a pause or dwell in this position. The groove may be formed with a like straight portion at the opposite side of the cam to give the finger a slight pause in its rearmost position and thereby 15 give time for the finger to rise into engagement with the package. The cam groove is so shaped as to quickly advance the feed finger and retract it rapidly during the time the secondary wrapper head is 20 passing through the portion indicated in Fig. 14.

In order to smooth or iron the ends of the package as they are forced into the tertiary folding slot, I may provide spring pressed 25 members 226, 226 which are pivoted to the bars 195, at 227 with their forward ends extending slightly into the sides of the receiving end of the tertiary folding slot. The ends of the presser members are grooved 30 to receive the ends of the package, as indicated in dotted lines in Fig. 5 in full lines in Figs. 14 and 15. The inner edges of the forward ends of the said presser members are curved so as to flare away from each 35 other and thereby facilitate the entrance of the package between them. The said presser members are held yieldingly in their innermost positions by springs 230, 230 that surround screw-threaded rods 231, 231 which 40 extend through the presser members and into the bars 195, the springs being interposed between the presser members and the heads of said screws. The inward movement of said presser members is limited by 45 engagement thereof with the bars 195, or otherwise. Said presser members are provided with lateral extensions or finger pieces 233, 233 by which they may be manipulated.

The completely wrapped packages are discharged from the end of the tertiary folding slot into and through an upwardly curved chute 235 of channel cross section suitably fixed to the machine frame and extending at its lower, receiving end adjacent 55 to the level of the said slot. At the lower or receiving end of the chute and at the delivery end of the tertiary folding slot is located a rotative screw wheel or disk 236 which is carried by the upper end of the vertical shaft 184, before referred to (Figs. 2, 3, 4 and 5). Said disk is notched at one part and one of the edges of the notch is turned down below the other edge of the 60 notch a sufficient distance to permit a package to enter between the edges. The disk 65

turns in the direction indicated by the arrows in Fig. 4 and Fig. 5, so that the lower or sharpened edge thereof passes beneath a package during the rotation of the disk through the slot 130; and the succeeding 70 packages picked up by the screw disk force the other packages through the chute. The packages may be removed from the chute by hand or otherwise discharged therefrom.

The upper wall plate of the secondary folding slot is removably supported on the lower plate or parts thereof, and is held pressed onto its seat by means of a spring held, bifurcated presser member 240 which bears on a transverse member 241 fixed to the upper wall plate. Said presser member 240 is swingingly mounted on a shaft 242 which extends laterally from a bearing 243 carried by the adjacent frame web 21. The 80 said presser member is normally pressed against said upper wall plate by means of a spring 245 (Fig. 3) attached to the frame and to a tail 246 of the presser member. The downward movement of said presser member is limited, when the top wall plate is removed, by means of a stop 248, attached to the shaft 242 on the side of the web 21 remote from the presser member, said stop being adapted to engage a transverse web 95 249, or other fixed part of the frame. The shaft is provided at its other end with a hand lever 250 by which it may be manipulated to raise the presser member from the wall plate. The transverse member 241 is 100 provided with a laterally extending hand piece 252 by which to remove the said top plate of the secondary folding slot, when the presser member is released.

Any suitable means may be employed for 105 driving the shafts of various mechanisms, herein described. The primary and secondary wrapper heads are rotated in unison at the same speed, and are shown in Fig. 1 as being driven by the intermeshing gear 110 wheels 254, 255 fixed to their respective shafts. The shafts of said primary and secondary wrapped heads may be rotated in unison by the same means as are the shafts of the primary and secondary wrapper heads of the machine shown in my co-pending application for U. S. Letters Patent, Serial No. 656,504, filed October 24th, 1911. The paper cutting and feeding device for the thin wrapper, the shaft 106 115 which drives the stripper roll 100 and the shaft 101 which is geared to and operates the paste applying finger, the paste disk and the feed finger slide may be driven by means of a sprocket belt 257 engaging suitable 120 sprocket wheels on the several shafts, as indicated in the dotted lines in Fig. 1, the said sprocket belt 257 being trained about a pulley 258 that is driven by the belt 259 125 trained about a sprocket wheel on the main 130

drive shaft 22. The gear wheels 254, 255 associated with the primary and secondary wrapper heads may be connected to the train of gears indicated in Fig. 1 in any suitable 5 or preferred manner as will be evident, timed to correspond with the timing of the other parts of the machine.

While the structural details of the illustrated embodiment of the invention have 10 been described with considerable particularity, it is to be understood that the invention in its broader features, is not limited to such details except as hereinafter made the subject of specific claims and as 15 imposed by the prior art.

I claim as my invention:—

1. A wrapping machine provided with a folding slot, and with an intermittently rotative wrapper head in rear thereof having 20 an intermediate pocket of less length than the articles to be wrapped, means for presenting articles and wrappers to the slot, means for advancing the articles and wrappers through the slot and for carrying 25 them to the wrapper head, said wrapper head being provided at the sides of said pocket with bearings to support the ends of the wrapper which project without the pocket, and means in advance of the head to complete the folding of the wrappers about the articles.

2. A wrapping machine provided with a folding slot, and with an intermittently rotative wrapper head in rear thereof, means 35 for presenting articles and wrappers to the slot, a plunger for advancing the articles and wrappers through the slot and for carrying them to the wrapper head, said wrapper head being provided at its sides 40 with bearings to support the end flaps of the wrapper, and said plunger being provided with extensions which overlap said bearings at the limit of its forward stroke, said bearings being cut away to permit rotative movement of the head while said plunger overlaps the same, and means in advance of the head to complete the folding 45 of the wrappers about the articles.

3. In a wrapping machine, a wrapper 50 head provided with pockets which open in opposite directions, and provided at the sides of the pockets with enlargements constituting bearings for the ends of the wrappers partially folded upon articles within 55 said pockets.

4. In a wrapping machine, a wrapper 60 head provided with pockets which open in opposite directions, and provided at the sides of the pockets with enlargements constituting bearings for the ends of the wrappers partially folded about articles within 65 the pockets, said enlargements being recessed or cut away in line with the pockets and on the sides thereof toward which the

5. A wrapping machine provided with a primary and a secondary folding slot or way arranged end to end, an intermittently rotative wrapper head between said slots and provided with pockets, a bar arranged 70 transversely of the secondary folding slot and of a length substantially equal to the length of a wrapper, to support the trailing edge of a wrapper when an article and wrapper are brought into line with the secondary folding slot and provided with end flap folding surfaces, and means in advance 75 of the head associated with the secondary folding slot to complete the folding of a wrapper about the article.

6. A wrapping machine provided with a primary and a secondary folding slot or way arranged end to end, an intermittently rotative wrapper head between said slots provided in line with said slots with pockets, 80 a bar arranged transversely over and fixed to the upper wall of the secondary folding slot and of a length substantially equal to the length of a wrapper, to support the trailing edge of a wrapper when an article and wrapper are brought into line with the secondary folding slot, and end folding means associated with the secondary folding slot, the upper wall of the secondary folding slot being removably supported on 90 the machine, and said transverse bar being arranged to steady or support the upper wall of said secondary slot.

7. A wrapping machine provided with a primary and a secondary folding slot or 100 way arranged end to end, an intermittently rotative wrapper head between said slots provided in line with said slots with pockets, and a bar arranged transversely over and fixed to the upper wall of the secondary folding slot and of a length substantially 105 equal to the length of a wrapper, to support the trailing edge of a wrapper when an article and wrapper are brought into line with the secondary folding slot, the upper wall of the secondary folding slot being removably supported on the machine, with means for holding it in place, and said transverse bar being provided with extensions that engage parts fixed to the machine 110 to support the rear end of the upper wall of the said secondary slot.

8. In a wrapping machine for applying 115 wrappers to articles wherein the end flaps are folded flat against the package, end flap folding mechanism comprising, in combination with upper and lower members between 120 which are formed a slot or way, of fixed plates at the side of said slot having folding surfaces which incline upwardly and rearwardly from the bottom of the slot, the upper member, abreast the folding plates, being made narrower than the lower member to form spaces to receive the upturned 125 end flaps, and said upper member being 130

- provided in advance of the folding plates with converging edges which extend at their rear ends inwardly beyond the sides of the slot, and a bar attached to and extending across the forward end of the upper wall member of the slot to constitute a support for the trailing edges of the wrappers delivered, together with articles partially wrapped therein, to the receiving end of the slot, said transverse bar having at its ends extensions which engage fixed parts on the lower wall member to support the forward end of the upper wall member. 5
9. In a wrapping machine for applying wrappers to articles wherein the end flaps are folded flat against the package, end flap folding mechanism comprising upper and lower members between which is formed a slot or way, fixed folding plates at the sides of the slot having folding surfaces which incline rearwardly and upwardly from the bottom of the slot, the said upper member, abreast the folding plates, being made narrower than the lower member to form spaces 20 to receive the upturned end flaps, and said upper member being provided in rear of the folding plates with converging edges which extend at their rear ends inwardly beyond the sides of the slot, said upper wall member being removably supported on the lower wall member, and a spring held lever pivoted to the machine frame and bearing on the upper wall member to hold the latter in place. 25
- 35 10. In a wrapping machine for applying wrappers to articles wherein the end flaps are folded flat against the package, end flap folding mechanism comprising upper and lower members between which is formed a slot or way, fixed folding plates at the sides of the slot having folding surfaces which incline rearwardly and upwardly from the bottom of the slot, the said upper member, abreast the folding plates, being made narrower than the lower member to form spaces 40 to receive the upturned end flaps, and said upper member being provided in advance of the folding plates with converging edges which extend at their rear ends inwardly beyond the sides of the slot, said upper wall member being removably supported on the lower wall member, a spring held lever pivoted to the machine frame and bearing on the upper wall member to hold the latter in place, a stop arm carried by said lever, and a fixed stop on the frame for engagement with said arm, for the purpose set forth. 45
- 50 11. In a wrapping machine, end flap folding mechanism comprising, in combination with the upper and lower members of a slot or way, of fixed members at the sides of the slot having inclined folding surfaces and a member at the receiving end of the slot to constitute a support for the trailing edge of a wrapper delivered together with an arti- 55
- cle partially wrapped therein to the receiving end of said slot, and provided also with end flap folding surfaces. 60
12. A wrapping machine provided with a folding slot or way, means for delivering an article and a wrapper to the slot, means to advance the article and wrapper therethrough and to fold one side of the wrapper upon the article, means at the discharge end of the slot for tucking in the rear margins of the extended end flaps of the wrapper, and means in advance of said slot to complete the folding of the wrapper about said article. 70 75
13. A wrapping machine provided with a folding slot or way, means for delivering an article and wrapper to the slot, a plunger to advance the article and wrapper therethrough and to fold one side of the wrapper upon the article, said plunger being provided at its side margins with longitudinal grooves, means at the discharge end of the slot to coöperate with the grooved plunger to tuck inwardly the rear margins of the extended end flaps of the wrapper, and means in advance of said slot to complete the folding of the wrapper about the article. 80 85 90
14. A wrapping machine provided with a folding slot or way, means for delivering an article and wrapper to the slot, means to advance the article and wrapper therethrough and to fold one side of the wrapper upon the article, fixed tucker plates extending into the slot to engage the edges of the partially folded end flaps of the wrapper, said plunger being provided at its sides with grooves to pass over said tucker plates, and means in advance of said slot for completing the folding of the wrapper about the article. 95 100
15. A wrapping machine provided with two folding slots arranged end to end, an intermittently rotative wrapper head between said slots having a pocket to receive an article and its wrapper from one slot and adapted, by rotation thereof, to carry same to the receiving end of the other slot, means for feeding a wrapper between one of said slots and said wrapper head, means for forcing the article from said first slot, together with its wrapper, into the pocket of said head to fold the wrapper about one side of the article, and means for forcing the article and wrapper from said head into the second slot to complete the side folding of the wrapper about the article, said wrapper head being provided with a guide extension to constitute means for guiding the wrapper into position in front of the pocket. 105 110 115 120 125
16. A wrapping machine provided with a folding slot, a wrapper head at the receiving end thereof provided with a pocket, means for delivering a wrapper across said pocket, and means for presenting an article against the wrapper and forcing the same, together with the article, into said pocket to fold the wrapper about one side of the article, and to 130

force the article and wrapper into said slot to fold the wrapper about the other side of the article, said wrapper head being provided with curved guides arranged to direct 5 the wrappers which are fed across the said pocket.

17. A wrapping machine provided with a slot, an intermittently rotative wrapper head at the receiving end thereof, provided with a 10 pocket, a wrapper receiving recess arranged at the receiving side of said pocket, means to deliver a wrapper to said recess, said head being provided with an extension to constitute a portion of one wall of the recess, means 15 to force an article, across the wrapper and into the pocket with the wrapper to fold the wrapper about one side of the article, and means to force the article and wrapper from the head into said slot to fold the other side 20 of the wrapper about the article.

18. A wrapping machine provided with a folding slot, a rotative wrapper head at the receiving end thereof provided with a through pocket, a slidable plate in said 25 pocket narrower than the length of the pocket, a removable locking and guiding pin for said plate, means for presenting an article with a wrapper to said pocket and against said plate, whereby the plate is 30 forced to the other end of the pocket, so that after the head is turned one-half rotation the delivery of the next article and wrapper to the head will act through said plate to force the article and wrapper into the slot and 35 thereby complete the folding of the wrapper about the article.

19. A wrapping machine provided with a folding slot, a rotative wrapper head at the receiving end thereof provided with a 40 through pocket, and a plate narrower than the length of the pocket, and slidable lengthwise therein, with means for guiding the plate comprising a pin extending through one wall of the head and into a slot in the 45 plate and a spring fixed to the head and engaging said pin and provided with a finger piece, combined with means for delivering an article and wrapper to said pocket, and coöperating with the slidable plate to discharge the article and wrapper from said 50 head to said slot to thereby fold the wrapper about the article.

20. A wrapping machine provided with a wrapping slot, a rotative wrapper head at 55 the receiving end thereof provided with a pocket, means for delivering a wrapper and article to the pocket to fold the wrapper about one side of the article, means to force the article and wrapper from the pocket 60 into the slot to fold the wrapper about the other side of the article, said wrapper head being provided at its ends with oppositely extending curved guides, arranged to direct the wrappers which are presented to the 65 head, and a reciprocating finger to force the

packages through the slot, said curved guides being notched to clear said finger.

21. A wrapping machine provided with a folding slot, a rotative wrapper head at the receiving end thereof provided with a 70 pocket, means to deliver a wrapper and article to the pocket to fold one flap of the wrapper about the article, means to deliver the wrapper and article from the head to the slot to fold the flap of the wrapper about 75 the article, means for applying paste to the latter flap, said wrapper head being provided at the upper and lower sides of its ends with spaced ribs over which the paste bearing flap wipes as the wrapper and article are delivered to said slot.

22. In a wrapping machine a rotative wrapper head provided with a through pocket and provided at its ends with oppositely extending wrapper guides which project above and below said head.

23. A rotative wrapper head provided with a through pocket and provided at the upper and lower sides of its opposite ends with spaced ribs elongated in planes parallel to the plane of the slot over which one flap of a wrapper wipes as the wrapper and an article are discharged from the head.

24. A wrapping machine provided with a slot, an intermittently rotative wrapper head at the receiving end thereof provided with a pocket, means to deliver a wrapper and an article to said pocket to fold one flap of the wrapper about the article, means to force the article and wrapper from the 95 head to the slot to fold the remaining flap of the wrapper about the article, there being a paste face at the receiving end of the slot against which the trailing flap is adapted to lie, and a rotative paste applying device having means to carry it across the trailing flap.

25. A wrapping machine provided with a slot, an intermittently rotative wrapper head at the receiving end thereof provided with a pocket, means to deliver a wrapper and an article to said pocket to fold one flap of the wrapper about the article, means to force the article and wrapper from the head to the slot to fold the remaining flap 110 of the wrapper about the article, there being a paste face at the receiving end of the slot against which the trailing flap is adapted to lie, and a revolving paste applying finger having a projection to travel across the trailing flap, with means to rotate the projection while in contact with the flap, and means for applying the paste to the said projection.

26. A wrapping machine provided with a slot an intermittently rotative wrapper head at the receiving end thereof provided with a pocket, means to deliver a wrapper and an article to said pocket to fold one 125 side of the wrapper about the article, means 130

to force the article and wrapper from the head to the slot to fold the remaining flap of the wrapper about the article, there being a paste face at the receiving end of the slot 5 against which the trailing flap is adapted to lie, and a rotating paste applying device having means to carry it across the trailing flap and a revolving paste applying finger having a projection to travel across the 10 trailing flap, with means to rotate the projection while in contact with the flap, combined with a rotative paste disk in line with said pasting face across which said projection of the pasting finger travels in the 15 revolutions of the pasting finger.

27. A wrapping machine provided with a slot, an intermittently rotative head at the receiving end thereof provided with a pocket, means to deliver a wrapper and an 20 article to said pocket to fold one flap of the wrapper about the article, means to force the article and wrapper from the head to fold the remaining flap of the wrapper about the article, there being a paste face at the 25 receiving end of the slot against which the trailing flap is adapted to lie, and a revolving paste applying finger having a projection to travel across the trailing flap, with means to rotate the projection while in contact with the flap, and means for applying the paste to said projection, said pasting face being provided in line with the path of the finger projection with a recess, for the 30 purpose set forth.

28. A wrapping machine provided with a slot, an intermittently rotative wrapper head at the receiving end thereof provided with a pocket, means to deliver a wrapper and an article to said pocket, means to discharge 40 said partially wrapped article into the slot to complete the folding of the wrapper about the article, a finger in the slot reciprocable toward and from the receiving end thereof and provided with a hook to engage the 45 packages to force them through the slot, and a spring acting on said finger to normally press the finger toward the packages in the slot, while permitting the finger to be depressed beneath an incoming package, the 50 forward end of the finger being inclined or tapered.

29. A wrapping machine provided with a slot, an intermittently rotative wrapper head at the receiving end thereof provided with a 55 pocket, means to deliver a wrapper and an article to said pocket, means to discharge the partially wrapped article into the slot

to complete the folding of the wrapper about the article, and a finger in the slot reciprocable toward and from the receiving end 60 thereof and provided with a hook to engage the packages to force them through the slot, the lower wall of said slot comprising a series of smoothing rollers, and the upper wall comprising a spring pressed plate. 65

30. A wrapping machine provided with a slot, an intermittently rotative wrapper head at the receiving end thereof provided with a pocket, means to deliver a wrapper and an article to said pocket, means to discharge the 70 partially wrapped article into the slot to complete the folding of the wrapper about the article, means to advance the packages through the slot, and concave faced presser arms extending into the sides of the slot at 75 the receiving end thereof to press the ends of the packages as the same are delivered to the slot.

31. A wrapping machine provided with a slot, an intermittently rotative wrapper head 80 at the receiving end thereof provided with a pocket, means to deliver a wrapper and an article to said pocket, means to discharge said partially folded article from the pocket into the slot to complete the folding of the 85 wrapper about the article, and means to advance the packages through the slot, the lower wall of said slot comprising a series of smoothing rollers and the upper wall comprising a spring pressed plate. 90

32. A wrapping machine provided with a slot, an intermittently rotative wrapper head at the receiving end thereof provided with a pocket, means to deliver a wrapper and an article to said pocket, means to discharge 95 said partially wrapped article from the pocket into the slot to complete the folding of the wrapper about the article, means to advance the packages through the slot, the lower wall of said slot comprising a series 100 of smoothing rollers, and the upper wall comprising a spring pressed plate and a spring mounted presser roller extending beyond the upper spring plate of the slot to engage the packages as they are delivered 105 to said slot.

In testimony, that I claim the foregoing as my invention I affix my signature in the presence of two witnesses, this 23rd day of January, A. D. 1913.

HARRY YARRINGTON ARMSTRONG.
